UNITED STATES PATENT OFFICE.

JOHN S. CRARY, OF SALEM, NEW YORK.

IMPROVEMENT IN METALLIC CARTRIDGES.

Specification forming part of Letters Patent No. 117,388, dated July 25, 1871.

To all whom it may concern:

Be it known that I, JOHN S. CRARY, of Salem, in the county of Washington and State of New York, have invented certain Improvements in Metallic Cartridges, of which the following is a specification, reference being had to the accompanying drawing.

My invention relates to metallic cartridges; and the invention consists in constructing the shell with two or more chambers, containing powder of different qualities arranged to be ignited one after the other, so as to form an accelerating charge, as hereinafter more fully explained.

Figure 1 is a longitudinal section of a rim-fire cartridge made on my plan. Fig. 2 is a similar view of a central fire-cartridge embodying my improvement, and Fig. 3 is a transverse section on the line *x x* of Fig. 2.

In constructing my improved cartridge I provide a metallic shell, A, made in the usual form, and within this outer shell A I place another shell, B, the two being arranged concentrically, as represented in Fig. 3, thereby forming two chambers for receiving the powder. As shown in Figs. 1 and 2, the outer shell A should be enough longer than the inner one to fit securely over the rear portion of the bullet, to which it is snugly fitted, as is usual in this class of cartridges. If it be desired to make it a rim-fire, then the two shells may be formed with closed heads or bases, as represented in Fig. 1; the outer one having a cavity in its rim or flange for receiving the fulminate D, as represented. The head or base of the two shells may be indented when formed so as to insure their being concentric when united, and I prefer to solder or otherwise secure them together. The inner shell B may have its rear end left open and its edge be fitted in an annular recess formed for it in the head of the outer shell, which will assist to secure it in place and facilitate the soldering of it fast, as the solder may be placed in the recess, the inner shell be inserted, and the soldering effected by simply placing them upright on a suitable furnace or plate properly heated. When thus made the fulminate is inserted in the rim, the outer chamber filled with coarse or slow-burning powder, and the inner or central cham-

ber then filled with a finer or quick-burning powder, and the ball inserted in the mouth of the outer shell and fitting close over the open end of the inner shell B. If preferred, the bullet C may be made with a groove, E, in its base, into which the front end of the inner shell will fit, as represented in Figs. 1 and 2. When such a cartridge is fired, the fulminate D will first ignite the powder in the outer chamber, and as the ball moves forward the flame from the outer chamber will ignite the powder at the front end of the inner chamber, which will then follow up the bullet with a more powerful pressure. If it be desired to construct it as a central-fire cartridge, then the shells may be constructed as represented in Fig. 2, in which the outer shell A has a hole formed in the center of its head or base, and the inner one has its head struck up in the form of a nipple or anvil, on which a cap, D', can be placed, through the opening in the head of A. Or, if preferred, both of the shells may be thus struck up in the form of a nipple or anvil, in which case soldering may be dispensed with. In this the central charge will be ignited first, and therefore the slower-burning charge in such case is placed in the inner or central chamber and the quicker-burning charge in the outer chamber.

It is obvious that the comparative capacity of the chambers may be varied as desired when making the shells. It is also obvious that the same quality of powder may be used in both chambers if desired; but I deem it better to use a quicker charge in the chamber last fired, and with that view I propose to use in the chamber last ignited gun-cotton or any similar explosive in order to increase its power.

Having thus described my invention, what I claim is—

A cartridge, composed of two separate charge-chambers, each filled with powder or its equivalent, and provided with fulminate or a cap, whereby it can be exploded in the ordinary breech-loading arms, substantially as set forth.

JOHN S. CRARY.
